UNITED STATES PATENT OFFICE.

HERMANN SELTMANN, OF POTTSTOWN, PENNSYLVANIA.

JUNIOR FOOT-REST.

1,164,127.

Specification of Letters Patent. Patented Dec. 14, 1915.

Application filed August 22, 1914. Serial No. 858,065.

To all whom it may concern:

Be it known that I, HERMANN SELTMANN, a citizen of the United States, residing at Pottstown, in the county of Montgomery and State of Pennsylvania, have invented 5 new and useful Improvements in Junior Foot-Rests, of which the following is a specification.

This invention is an improved foot rest 10 for use in connection with a shoe shining chair and stands to support the foot of a child or small person when shining his shoes, the object of the invention being to provide a junior foot rest which may be 15 readily applied to and removed from a shoe polishing stand to accommodate a child and enable his shoes to be polished as readily as those of a grown person.

The invention consists in the construction, 20 combination and arrangement of devices hereinafter described and claimed.

In the accompanying drawings:—Figure 1 is a side elevation of a junior foot rest illustrating an embodiment of my invention 25 and showing same arranged for use in connection with the foot rests and platform of a shoe shining seat or chair. Fig. 2 is a front elevation of the same. Fig. 3 is a detail plan of the same. Fig. 4 is a vertical 30 longitudinal sectional view of the same. Figs. 5—6 are detail transverse sectional views on the planes indicated respectively by the lines *a—a* and *b—b* of Fig. 3.

For the purposes of this specification a 35 chair such as used in shining shoes is indicated at 1, its step platform at 2 and the usual stands or foot rests for the feet of grown up people are indicated at 3.

My improved foot rest is indicated, in one 40 embodiment thereof, at 4 and is provided with a supporting tripod 5 which comprises a rear arm 6 the lower end of which is adapted to rest in the angle between the steps of the platform and a pair of side 45 arms 7—8 which are respectively adapted to rest at their lower ends on the foot rests 3.

The plate 9 of the foot rest is of the general shape of the bottom of a shoe and is

here shown as provided at a point a suitable 50 distance from its heel or rear end with a supporting fork 10 which is extended upwardly from the tripod 5. On the under side of the plate 9 is a centrally and longitudinally arranged guide and housing 11 in 55 which longitudinally extending bars 12—13 are slidably mounted which on account of their position beneath the plate 9 will be termed toe and heel bars. The toe bar is provided with a pair of clamps 14 to engage 60 the sole, at the toe, and these clamps are pivotally connected to the bolt 12 as at 15. The heel bar 13 is here shown as provided with a pair of integral or rigid heel clamps 16. The heel bar is also provided with a 65 lug 17 which extends downwardly therefrom. The toe bar 12 has a downwardly extending handle 18. A coiled spring 19 has its ends attached to the lug and handle and said spring exerts its tension to draw 70 the toe and heel bar toward each other. On the upper side of the plate 9, at a suitable distance from its rear end is a shoulder or stop 20 to engage the front side of the heel.

It will be understood from the foregoing 75 that the improved junior foot rest may be readily used in connection with the ordinary foot rest of a shoe shining chair or stand to accommodate a child or small person and may be used for either one or both feet. 80

Having thus described my invention, I claim:—

1. A foot rest of the class described having a plate conforming substantially to the shape of the shoe, a housing secured to the 85 under side of said plate and providing a guideway, bars loosely mounted in the guideway and extending beyond the same at opposite ends thereof, shoe clamping members carried by the projecting ends of said bars, depending lugs formed integral with said bars and arranged adjacent the shoe clamping members, a spring terminally connected with said lug to cause the same to contact with the ends of the housing and limit the movement 90 of the bars in one direction, an extension on one of the said lugs providing a handle whereby one of the bars may be slid longitu- 95

dinally of the housing against the influence of the spring.

2. A supplemental foot rest for use upon shoe shining stands and having two front legs of unequal length arranged to be supported by the two foot rests upon the stand, and a rear leg of greater length than either of the two front legs for contact with the

angle between the steps of the stand distant from the foot rest thereon.

10

In testimony whereof I affix my signature in presence of two witnesses.

HERMANN SELTMANN.
